UNITED STATES PATENT OFFICE

106,282

DESIGN FOR A DRESS ENSEMBLE

Lillian Burke, New York, N. Y.

Application August 11, 1937, Serial No. 70,985

Term of patent 3½ years

To all whom it may concern:

Be it known that I, Lillian Burke, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear jacket portion is conventional.

The sleeve and bolero edges are contrastingly piped, and conform in color to the inner lining of the neckline bow.

I claim:

The ornamental design for a dress ensemble, substantially as shown, and described.

LILLIAN BURKE.
